UNITED STATES PATENT OFFICE.

EDGAR O. HATTEN, OF EVANSTON, WYOMING.

VIBRATOR.

1,389,586.

Specification of Letters Patent.

Patented Sept. 6, 1921.

Application filed July 18, 1919. Serial No. 311,901.

To all whom it may concern:

Be it known that I, EDGAR O. HATTEN, a citizen of the United States, residing at Evanston, in the county of Uinta and State 5 of Wyoming, have invented a new and useful Improvement in Vibrators, of which the following is a specification.

One object of my invention is to provide a vibrator that will draw air through the 10 applicator in such a manner that all the impurity of the skin will be drawn out of the pores as the applicator vibrates.

Another object of my invention is to provide a vibrator in such a manner that it can 15 be used for drying the hair. Another object of my invention is to provide a vibrator with a fan and suction.

With these and other objects in view my 20 invention consists of the following arrangements of parts, to be hereinafter described and claimed, reference being had to the drawings forming part of this specification and to the figures of reference marked thereon.

25 Figure 1 is a view with the cover removed showing the interior in place.

Fig. 2 is an outside view showing the cover in place.

Similar letters and numbers refer to like 30 parts through the drawings.

A is the motor within the casing. The casing is composed of a front and back section B and B', the handle D being on the back section B'. C are the handles of the circuit 35 breaker, 1 the brushes, 2 the armature.

As the motor used in this invention is of standard make I will not describe the other parts of it.

3 is the driving shaft to which is secured 40 the motor A, the fan 4 and the gear 5. The gear 5 operates another gear 6 which is mounted on a pin 7 secured within the lug 8 which is part on one section and part 45 on the other section of the casing and is clamped over the pin 7 when the sections are together, thus holding the pin in place.

Attached at one end to the gear 6 is a pitman rod 9 and the other end being attached to a sleeve 10 sliding on the driving 50 shaft 3. This sleeve 10 answers as a pump for drawing the air into the casing. On the sleeve 10 are located a number of valves 11 that close on the upper stroke of the sleeve and open on the downward stroke.

55 The lower end of the driving shaft is se-

cured in the bearing 12 while the upper end is secured in the bearing 12'.

One end of the spring 13 is secured in the center of the lower end of the driving shaft 3 while the other end is secured to the 60 driven shaft 14 and placed off of center so as to give the driven shaft an oscillating movement when the driving shaft revolves. Placed in the upper end of the driven shaft 14 is a valve 15 for closing the hole 16 65 through the driven shaft. The driven shaft being enlarged at 17 so as to form a ball bearing which fits within the socket 25 formed by the two sections B and B' thus giving the free movement to the vibrator 70 cup 18. The thumb screw 18' in the driven shaft 14 regulates the intake of air through the hole 16.

After the casing B and B' have been secured together by screws 19 the drier cap 75 26 is screwed on. The motor is secured within the casing by means of screws 20. Within the opening 21 is placed a slide 21' which moves with the handles on the circuit breaker to prevent the air from 80 escaping as it is forced through the vibrator by the fan.

Having thus described the parts of my invention I will illustrate the operation of same.

85 When the electric current is turned into the motor it will revolve and operate the driving shaft 3 which in turn operates the fan 4 and the gear 5. The gear 5 operates the gear 6 which operates the pitman rod which operates the sleeve 10, thus raising the sleeve up and forming a suction through the hole 16 in the driven shaft 14. As the sleeve is drawn up the valves 11 will close and the valve 15 will 90 open thus allowing the air to be drawn in through the hole 16. On the downward stroke of the sleeve the valves 11 are opened and the valve 15 is closed, thus allowing the air to be drawn in by the fan 4 and forced 100 out of the hole 22 in the driving shaft 3 and the holes 23 in the side of the casing and out of the drier cap 26.

Having thus described my invention what I claim as new and desire to secure by Letters Patent is:

1. A vibrator of the character described in combination with a casing, a motor mounted within said casing, means for operating said motor, a driving shaft secured 110

to said motor, said driving shaft being journaled within said casing, a gear secured to said driving shaft for driving another gear, the other gear, said other gear being secured 5 to the side of said casing, a pitman rod attached to said other gear and to a sliding sleeve, the sliding sleeve, said sliding sleeve mounted on said driving shaft, the valves within said sliding sleeve for preventing the 10 return of air through the holes within said sliding sleeve when said sliding sleeve is moved upward by said pitman rod, a spring on the lower end of said driving shaft for connecting said driving shaft with a driven shaft, the driven shaft and a cup secured to 15 said driven shaft.

2. A vibrator of the character described in combination with a casing, a motor secured within said casing, means for operating 20 said motor, a driving shaft secured to said motor, said driving shaft being journaled within said casing, a gear secured to said driving shaft for driving another gear, the other gear, said other gear being mounted 25 on a shaft secured in the wall of said casing, a pitman rod attached to said other gear and to a sliding sleeve on said driving shaft, said gear other gear and pitman rod for operating said sliding sleeve on said 30 driving shaft, the sliding sleeve, valves within said sliding sleeve for preventing the return of air through holes within said sliding sleeve when said sliding sleeve is moved upward by the said pitman rod, a spring on the lower end of said driving shaft for connecting 35 said driving shaft with a driven shaft, the driven shaft and a cup secured to said driven shaft.

3. A vibrator of the character described 40 in combination with a casing, a motor mounted within said casing, a driving shaft secured to said motor, said driving shaft being journaled within said casing, a fan secured to said driving shaft, said fan for 45 forcing air through said casing, a gear mounted on said driving shaft for driving another gear, the other gear, said other gear being mounted on a shaft secured in the wall of said casing, a pitman rod secured 50 to said other gear and to a sliding sleeve, the sliding sleeve, said sliding sleeve operating on said driving shaft, said gear, other gear and pitman rod for operating said 55 sliding sleeve, a driven shaft attached to said driving shaft by means of a spring, the spring and a cup secured to said driven shaft.

4. A vibrator of the character described

in combination with a casing, a motor mounted within said casing, a driving shaft 60 secured to said motor, said driving shaft being journaled within said casing, a fan secured to said driving shaft for forcing air through said casing, a gear mounted on said driving shaft for driving another gear, the 65 other gear mounted on a shaft secured within the wall of said casing, said other gear operating a pitman rod, the pitman rod attached to said other gear and to a sliding sleeve mounted on said driving shaft, said 70 pitman rod operating said sliding sleeve, valves within said sliding sleeve to prevent the return of air when said sliding sleeve is moved upward, a driven shaft operated by said driving shaft, a spring connecting said 75 driving shaft with said driven shaft, a cup, on said driven shaft.

5. A vibrator of the character described in combination with a casing, a motor mounted within said casing, mean for operating said 80 motor, a driving shaft secured to said motor, said driving shaft being journaled within said casing, a fan secured to said driving shaft for forcing the air out of said casing, a gear secured to said driving shaft for 85 driving another gear, the other gear, said other gear mounted on a pin secured within the wall of said casing, a pitman rod attached at one end to said other gear and the other end to a sliding sleeve mounted on said 90 driving shaft, said pitman rod for moving said sliding sleeve on said driving shaft, the sliding sleeve for drawing air into said casing, valves within said sliding sleeve to prevent the return of air when said sliding 95 sleeve is moved upward, a spring secured to the lower end of said driving shaft and to the upper end of a driven shaft to give the driven shaft and oscillating movement, the spring and driven shaft, said driven shaft 100 having a hole therein through which air is sucked when said sliding sleeve is moved upward, a valve located in the upper end of said driven shaft to prevent the return of air through said opening in said driven 105 shaft when said sliding sleeve is moved downward, a thumb screw located in said driven shaft for regulating the flow of air through said hole in said driven shaft, a stem on said driven shaft for receiving a 110 vibrator cup, said driving shaft being secured between the walls of said casing.

EDGAR O. HATTEN.
